RATCHET MECHANISM FOR SCREW-DRIVERS, &c.

977,957.

Specification of Letters Patent.

Patented Dec. 6, 1910.

Application filed May 22, 1909. Serial No. 497,649.

To all whom it may concern:

Be it known that I, GEORGE O. LEOPOLD, a citizen of the United States, residing in Philadelphia, Pennsylvania, have invented 5 certain Improvements in Ratchet Mechanism for Screw-Drivers, Drills, Etc., of which the following is a specification.

My invention relates to certain improvements in ratchet mechanisms especially applicable to screw drivers, ratchet drills and other small tools, but it is to be understood 10 that it can be used for other purposes without departing from the essential features of the invention.

15 The object of my invention is to simplify the ratchet mechanism, to reduce the number of parts, and to prevent the accidental displacement of the pawls when in engagement with the ratchet wheel.

20 In the accompanying drawing:—Figure 1, is a view of a screw driver showing the application of my improved ratchet mechanism; Fig. 2, is an enlarged view of part of Fig. 1, with the casing removed; Fig. 3, is a 25 longitudinal sectional view on the line 3—3, Fig. 2; Fig. 4, is a transverse sectional view on the line 4—4, Fig. 3; Fig. 5, is a transverse sectional view on the line 5—5, Fig. 3; Figs. 6, 7 and 8, are views showing the different 30 positions of the pawls; Fig. 9, is a perspective view of the ratchet wheel; Fig. 10, is a perspective view of the pawl; and Fig. 11, is a perspective view of the pawl spring.

35 A is the handle of a screw driver in the present instance. This handle has a portion D upon which is mounted the barrel D' forming a support for the spindle B and the ratchet mechanism.

40 In the present instance the ratchet mechanism can be shifted into three different positions, in the first position the handle will drive the spindle to the right and ratchet to the left; in the second position the parts 45 will be locked so that the spindle will turn with the handle as in an ordinary screw driver; and in the third position the handle will turn the spindle to the left and ratchet to the right, as illustrated in Figs. 6, 7 and 8.

50 The spindle B of the screw driver extends into the barrel D' which is secured to the handle A in any suitable manner, and the end b of the spindle is adapted to a bearing plate c within the barrel at the end of the 55 handle.

B' is the ratchet wheel having teeth cut as shown in Figs. 3, 4 and 5, and these teeth are beveled at each end b' as illustrated, so as to clear the pawls and also to allow the pawls to more readily enter the space between the teeth when they are shifted.

c' is a locking plate which projects through a slot in the barrel D' and in front of the ratchet wheel B, as indicated in Fig. 4.

The barrel D' is recessed for the reception 65 of the sliding pawl E which is made as shown in Fig. 10 in the present instance, and in order to form slideways for the pawl I notch the barrel at d on each side of the recess for the reception of the extensions e 70 and e' on the pawl. These extensions are connected together by a longitudinal member e² having a pin e³ in the present instance, which extends through the slot d² in the casing D² inclosing the barrel D'. Projecting inwardly from one of the extensions e is a pawl i and projecting inward from one of the extensions e' is a pawl i', both these 75 pawls are made integral with the slide E; the central portion e² of the slide being raised 80 sufficiently to clear the ratchet wheel B'.

In order to yieldingly hold the ratchet slide on its ways, I provide a spring G having ends g, g' which rest upon each end of the ratchet slide and have turned down portions g' on each side of the ends, as shown 85 in Fig. 11. These turned down portions rest on each side of the central member e² of the pawl e and also rest against the end members e, e' so that the spring must move 90 with the pawl. The spring is crimped at the center e² on each side of the hole through which the pin e³ passes; the hole in the spring being of such diameter as to receive the head of the screw pin, as illustrated in Figs. 3 and 5. The crimped portions g² are adapted to the notches d³ in the walls of the slot d², Fig. 1, so that the pawl 95 when shifted from one position to another is held in position by the crimped portion g² extending into the slots; the crimped portions being beveled at each side, as indicated in Fig. 10, allow the pawl to be shifted when pressure is applied.

The operation of the ratchet mechanism 105 is as follows:—The sliding pawl, when shifted to the position illustrated in Fig. 6, is in position to turn the spindle toward the right; the pawl i being in engagement with the ratchet wheel and the pawl i' being free 110

of the ratchet wheel, yet if the handle is turned toward the left the pawl will give and allow the handle to ratchet back to position. If the pawl is shifted to the center 5 position, then both pawl extensions *i*, *i'* engage the ratchet wheel and the wheel is thus locked against movement in either direction, so that the screw driver can be used the same as an ordinary plain screw driver. If the 10 sliding pawl is moved into the position shown in Fig. 8, then the pawl *i'* is in engagement and the pawl *i* is free and the spindle can be turned to the left by turning the handle, but when the handle is turned 15 to the right the pawl will ratchet so that the handle will turn without turning the spindle.

It will be noticed that the ends of the 20 pawls *i*, *i'* are beveled (Fig. 10), and by beveling the ratchet wheel, as shown, the pawls will, when moved forward, ride upon the ratchet wheel and into engagement. Furthermore, the beveling of the pawl enables it to more readily enter the spaces 25 between the teeth of the wheel.

I claim:—

1. The combination in ratchet mechanism, 30 of a support, a spindle mounted in the support, a ratchet wheel on the spindle, a sliding pawl piece having two pawls adapted to slide on the support, one of said pawls extending toward the center from one end of the pawl piece and the other extending toward the center from the other end of the 35 pawl piece, said pawl pieces lying parallel to the axis of the ratchet wheel, the pawls terminating short of the center so that they will not overlap, the width of the ratchet being less than the length of the pawl so 40 that either one or the other or both of the pawls will engage the ratchet wheel.

2. The combination in ratchet mechanism, 45 of a support, a spindle mounted in said support, a ratchet wheel on the spindle, a sliding pawl piece having end members and a connecting central member, the pawl extending from one end member toward the center at one side of the central member, a second pawl extending from the other end 50 member toward the center on the other side of the central connecting member, said pawls lying parallel to the axis of the ratchet wheel, the ends of the pawl stopping short of the center of the pawl piece so as not to 55 overlap, the said ratchet wheel being less in width than the length of the pawls so that the pawl piece can be shifted to throw into engagement either one or the other or both of the pawls with the ratchet wheel.

60 3. The combination of a barrel, a spindle mounted in the barrel and having a ratchet wheel thereon, the teeth of the ratchet wheel being beveled at each end, the barrel having slideways, parallel to the axis of the ratchet, 65 a sliding pawl piece having end members

adapted to the slideways and a central connecting piece with pawls projecting toward the center from each end piece, said pawls having beveled ends, and means for holding the pawl piece onto its slideways.

4. The combination of a barrel, a spindle 70 adapted to bearings in the barrel, a ratchet wheel on the spindle, a sliding pawl piece having pawls arranged to engage the ratchet wheel and having a central member, a spring mounted above the pawl piece and having projections resting on the end of the pawl piece and turned down portions extending on each side of the central member of the pawl piece so as to keep the spring central, 75 and a casing inclosing the above described parts.

5. The combination of a barrel, a spindle 80 mounted in the barrel, a ratchet wheel on the spindle, slideways on the barrel, a pawl 85 piece having a central member and end members, said end members resting upon the slideways, a pawl projecting from each end piece toward the center, a spring resting upon the pawl piece and held so as to move 90 with it, a casing, a slot in the casing having a series of notches in its walls, a pin projecting from the pawl piece through the slot in the casing, the spring having a central opening for the free passage of the pin 95 and having projections on each side of the opening adapted to enter the notches in the walls of the slot in the casing.

6. A pawl piece made of a single piece of metal having end members, a central longitudinal member connecting the end members and raised above the plane of the said end members, and a pawl projecting inward from each end member, one pawl being on one side of the central connecting member 100 and the other pawl being on the opposite side thereof, each pawl terminating short of the center of the pawl piece.

7. A spring for ratchet mechanism consisting of a body portion having ends shaped 110 to bear upon a pawl piece and having downwardly projecting portions at each end to hold the spring laterally to the pawl piece and having a central opening through which an operating pin may pass, and V-shaped 115 projections on each side of the central opening to engage notches in the inclosing casing of the ratchet mechanism to which the spring is applied.

8. The combination in a ratchet screw 120 driver, of a handle, a hollow barrel mounted on the end of the handle, a spindle, a ratchet wheel on the spindle, said ratchet wheel being mounted within the barrel, a bearing plate in the barrel receiving the inner end 125 of the spindle, a locking plate bearing against one end of the ratchet wheel and acting with the bearing plate to hold the spindle in position, said barrel having slideways, a one piece double pawl having exten- 130

sions resting on the slideways, said pawl having members shaped to engage the teeth of the ratchet wheel, a casing secured to the barrel and inclosing the mechanism, said 5 casing having a slot therein and notched on each side of the slot, a spring shaped at each end to engage the pawl so that it will slide with the pawl and having a projection adapted to enter the notches in the casing, a 10 pin projecting from the pawl and passing

through an opening in the spring and through the slot in the casing, and by which the pawl is shifted.

In testimony whereof, I have signed my name to this specification, in the presence of 15 two subscribing witnesses.

GEORGE O. LEOPOLD.
